ADOLF BARGEBOER, OF THE HAGUE, NETHERLANDS

ROTARY PUMP

Application filed May 14, 1929, Serial No. 362,989, and in Great Britain April 4, 1929.

My present invention, which relates to a rotary pump or compressor, more especially to a self-sucking rotary pump for liquids, gases or mixtures of these fluids, has for its principal object a pump of this type which, while simple and reliable in construction, is exceptionally efficient in operation. With this object in view, I suggest to provide the annular, crescent-shaped or otherwise formed channel between the circumferential portion of the blade wheel or impeller and the inner wall of the pumping space with inwardly extending shoots or branches forming recesses in one or in both side walls of said space.

In order that my invention may be clearly understood by one skilled in the art, I shall describe some embodiments thereof with reference to the annexed drawing, on which

Fig. 1 is a vertical, axial sectional elevation of a rotary pump,

Fig. 2 is an end elevational inner view of said pump and

Figs. 3-5 are inner elevational views of modified side walls of the pumping space.

In accordance with Figs. 1 and 2, the casting of the pump is composed of a casting 1 provided with a suction nozzle 3, and of a casting 2 having a liquid chamber 4 and a discharge nozzle 5. The shaft 6, which is supported by a bearing 7 and sealed by a stuffing box 8 both located in the casting 2, carries at its one end, intermediate between both castings 1 and 2, a blade wheel or impeller 9 secured thereto by means of a nut 10.

The pumping space has a cylindrical circumferential wall 11 which is eccentric with respect to the shaft 6 and the impeller 9, so that a crescent-shaped channel 12 is left between the circumference of the impeller and the said cylindrical wall 11. Said channel 12 has a plurality of shoots 13 forming recesses in both side walls of the pumping space, i. e. in the facing walls of castings 1 and 2, said shoots being inwardly and spirally bent in the direction of rotation of the impeller and closed at their inner ends. Within the channel 12, the casting 1 is provided with an inlet opening 14 and the casting 2 both with an outlet opening 15 and a back flow opening 16.

In the embodiments shown in Figs. 3-5, the impeller is assumed to be coaxial with and snugly fitting within the cylindrical pumping space, the channel 12 being located on one or, preferably, on either side of the impeller. In tangential direction, said channel 12 only extends segmentally from the inlet opening 14 to the outlet opening 15. In accordance with Fig. 3, one shoot 13 of the channel 12 is located intermediate between the end portion of said channel and the outlet opening 15. Fig. 4 shows an embodiment in which the last shoot partly registers with the outlet opening 15 and in which, moreover, the back flow opening 16 has been dispensed with. This is also the case in the embodiment illustrated in Fig. 5, in which the channel 12 is subdivided by bridges 17 into a plurality of segmental sections and in which the end sections are in communication with one another through a relatively narrow passage 18.

The described pump functions as follows:

Assuming the pump to be completely filled with water and the shaft to be rotating at high speed, then the impeller will throw the water in an approximately tangential direction into the channel 12. In normal operation, the water in said channel flows in substantially the same direction but at a much lower speed. Owing to the excess of speed of the inflowing water, both the speed and the pressure of the water in the channel 12 increase in the direction of motion of the impeller. Obviously, each shoot 13 will deviate part of the water in an inward direction, whereby the water is returned into the impeller and again accelerated, so that it is again thrown with full circumferential speed onto the water flowing through channel 12. Thereby, and also owing to the presence of local strictures that may be provided axially or radially in the channel 12, preferably just beyond the opening of each shoot 13 (see Fig. 4), the pressure rapidly increases in the direction of rotation of the impeller, so that the water is forcibly driven to the pressure side of the pump.

Initially, when the pump begins to suck, both the chamber 4 and the pumping space are

completely filled with water. If, now, the impeller is driven at high speed, it forces the water within the pumping space in outward direction. This causes a certain vacuum to set up, but as the pressure increases in the direction of rotation, said vacuum gradually decreases and after a certain time an overpressure is set up, so that the air is discharged thru the outlet opening. The spiral line 19 in Fig. 2 approximately indicates the inner circumference of the mass of water within the pumping space in this stage of the operation.

As the vacuum in the suction pipe of the pump increases, the pump requires an increased quantity of water, owing, inter alia, to the reduction of the amount of water within the pumping space. This condition is met by water from chamber 4 flowing back into the pumping space, either through the outlet opening 15 (Figs. 4 and 5), or through one or more special return flow openings 16 (Figs. 1-3), until the water in the suction pipe enters into and completely fills the pumping space.

The same purpose is served by the narrow channel 18 (Fig. 5) connecting the pressure and the suction ends of the channel 12 and through which a certain quantity of water from the pressure end of the channel 12 is delivered to the suction end of this channel, depending from the difference of pressure at both ends.

It will be understood that the described pump can as well be used as an air pump or as a compressor. If the pump does not require to draw in air or other gas, the outlet 15 may open into the circumferential channel 12.

The shoots 13 may be more or less, or even exactly radial and may have a variable cross sectional area.

It is preferred to provide the rotary impeller with flat, radial blades. A rearward curvature would tend to reduce the outlet velocity of the water, whereas a forward curvature would materially increase the internal resistance of the pump.

I wish it to be well understood that the expression "pump" in this specification and in the claims appended thereto is to be so broadly construed as to also cover a compressor.

What I claim is:

1. In a rotary pump, a casing enclosing a pumping space having two side walls, an impeller adapted for rotation within said space and fitting between said side walls, a channel formed between the circumferential portion of said impeller and the walls of said space, an inlet opening in one of said side walls and located within said channel, an outlet opening in one of said side walls, and a shoot of said channel extending inwardly and forming a recess in a side wall of said space.

2. In a rotary pump, a casing enclosing a pumping space having two side walls, an impeller adapted for rotation within said

space and fitting between said side walls, a channel formed between the circumferential portion of said impeller and the walls of said space, an inlet opening in one of said side walls and located within said channel, an outlet opening in the other side wall, and a plurality of shoots of said channel extending inwardly and forming recesses in a side wall of said space.

3. In a rotary pump, a casing enclosing a pumping space having two side walls, an impeller adapted for rotation within said space and fitting between said side walls, a channel formed between the circumferential portion of said impeller and the walls of said space, an inlet opening in one of said side walls and located within said channel, an outlet opening in the other side wall, and a shoot of said channel extending inwardly and forming recesses in both of said side walls.

4. In a rotary pump, a casing enclosing a pumping space having two side walls, an impeller adapted for rotation within said space and fitting between said side walls, a channel formed between the circumferential portion of said impeller and the walls of said space, an inlet opening in one of said side walls and located within said channel, an outlet opening in the other side wall, and a plurality of shoots of said channel each extending inwardly and forming recesses in both of said side walls.

5. In a rotary pump, a casing enclosing a pumping space having two side walls, an impeller adapted for rotation within said space and fitting between said side walls, a channel formed between the circumferential portion of said impeller and the walls of said space and having a variable cross sectional area, an inlet opening in one of said side walls and located within said channel, an outlet opening in the other side wall, and a shoot of said channel extending inwardly and forming a recess in a side wall of said space.

6. In a rotary pump, a casing enclosing a pumping space having two side walls, an impeller adapted for rotation within said space and fitting between said side walls, a crescent-shaped channel formed between the circumferential portion of said impeller and the walls of said space, an inlet opening in one of said side walls and located within said channel, an outlet opening in the other side wall, and a shoot of said channel extending inwardly and forming a recess in a side wall of said space.

7. In a rotary pump, a casing enclosing a pumping space having two side walls, an impeller adapted for rotation within said space and fitting between said side walls, a channel formed between the circumferential portion of said impeller and the walls of said space, an inlet opening in one of said side walls and located within said channel, an

outlet opening in the other side wall, and a shoot of said channel extending inwardly and forming a recess in a side wall of said space, the said channel being reduced in cross sectional area forward of the axis of said shoot reckoned in the direction of rotation of said impeller.

another thru a relatively narrow passage, an inlet opening in one of said side walls and located within said channel, an outlet opening in the other side wall, and a shoot of said channel extending inwardly and forming a recess in a side wall of said space.

5 70 In testimony whereof I affix my signature.

ADOLF BARGEBOER.

6 80 10. In a rotary pump, a casing enclosing a pumping space having two side walls, an impeller adapted for rotation within said space and fitting between said side walls, a channel formed between the circumferential portion of said impeller and the walls of said space, an inlet opening in one of said side walls and located within said channel, an outlet opening in the other side wall and registering with part of the said channel, and a shoot of said channel extending inwardly and forming a recess in a side wall of said space.

15 85 20. 9. In a rotary pump, a casing enclosing a pumping space having two side walls, an impeller adapted for rotation within said space and fitting between said side walls, a channel formed between the circumferential portion of said impeller and the walls of said space, an inlet opening in one of said side walls and located within said channel, an outlet opening in the other side wall, and a shoot of said channel extending inwardly and forming a recess in a side wall, said shoot registering with said outlet opening.

25 90 30. 10. In a rotary pump, a casing enclosing a pumping space having two side walls, an impeller adapted for rotation within said space and fitting between said side walls, a channel formed between the circumferential portion of said impeller and the walls of said space, an inlet opening in one of said side walls and located within said channel, an outlet opening in the other side wall, a shoot of said channel extending inwardly and forming a recess in a side wall of said space, and a return flow opening in the side wall which is provided with the said outlet

35 10 40. 11. In a rotary pump, a casing enclosing a pumping space having two side walls, an impeller adapted for rotation within said space and fitting between said side walls, a sectional channel formed between the circumferential portion of said impeller and the walls of said space, an inlet opening in one of said side walls and located within said channel, an outlet opening in the other side wall, and a shoot of said channel extending inwardly and forming a recess in a side wall of said space.

45 110 50. 12. In a rotary pump, a casing enclosing a pumping space having two side walls, an impeller adapted for rotation within said space and fitting between said side walls, a segmental channel formed between the circumferential portion of said impeller and the walls of said space the ends of said channel being in communication with one
